(57) **CLAIM**

The ornamental design for an enclosure of an electronic controller of a valve, as shown and described.

DESCRIPTION

FIG. 1 is a downward perspective view from a right rear corner of an enclosure of an electronic controller of a valve showing the new design;

FIG. 2 is a zoomed-in view of a downward perspective view from the right rear corner thereof;

FIG. 3 is a downward perspective view from a right front side thereof;

FIG. 4 is a downward perspective view from a right front corner thereof;

FIG. 5 is a downward perspective view from a left rear corner thereof;

FIG. 6 is top plan view thereof;

FIG. 7 is bottom plan view thereof;

FIG. 8 is a front elevational view thereof;

FIG. 9 is a rear elevational view thereof; and,

FIG. 10 is a right side elevational view thereof, wherein a left side elevational view is a mirror image of the right side elevational view.
